UNITED STATES PATENT OFFICE.

JOHANN F. BOEPPEL, OF DAVENPORT, IOWA.

DESIGN FOR A BUTTON.

SPECIFICATION forming part of Design No. 34,893, dated August 6, 1901.

Application filed July 8, 1901. Serial No. 67,553. Term of patent 3½ years.

To all whom it may concern:

Be it known that I, JOHANN F. BOEPPEL, a citizen of the United States of America, residing at Davenport, in the county of Scott and State of Iowa, have invented and produced a certain new and useful Design for Buttons, of which the following is a specification, reference being had to the accompanying drawings, in which—

10 Figure 1 is a plan view of my new design; Fig. 2, an edge elevation; Fig. 3, a section on the line 3 3 of Fig. 1; Fig. 4, a section on the line 4 4 of Fig. 1, and Fig. 5 a section on the line 5 5 of Fig. 1.

15 As will be seen from the drawings, this design consists of a circular body having a rounded edge *a* and a substantially star-shaped depression in its upper side, the star

having four points or arms *c*, which terminate short of the rounded portion of the edge *a* and are connected together at the center of the button. The sides of each depression *c* are rounded and concaved, and in the lowest part of each point is formed a thread-hole *d*, the four thread-holes being equidistant from each other and from the center.

I claim—

The design for a button substantially as herein shown and described.

In testimony whereof I hereunto affix my signature, in the presence of two witnesses, this 3d day of July, 1901.

JOHANN F. BOEPPEL.

Witnesses:

F. W. BEAL,

F. C. SUSEMIEHL.
